SANDING DRUM

Application filed December 29, 1927. Serial No. 243,235.

This invention relates to drums for abrading, polishing, and similar purposes, of the type used in various machines, such as those employed in working wood or polishing metal, leather, and the like, these drums being power driven and having a working surface which is brought into contact with the article to be operated on. The present drum is one capable of use in machines of numerous kinds, and while constructed primarily for use in portable machines for surfacing hard wood floors, its utility, as will be apparent from what follows, is by no means limited to that particular application.

In drums for working floors as now constructed, the working surface is provided by means of a sheet of abrasive cloth or paper wrapped around the surface of the drum. As this sheet performs the abrading action, it must be held tightly in position, and lie flat on the drum surface so as to be supported thereby, since otherwise it would slip, wear unevenly and become torn. The securing of the sheet to the drum is a problem of considerable difficulty and numerous attempts have been made to solve it. For example, the drum has been provided with a slot in its periphery into which the ends of the paper are passed, and slotted shafts are mounted within the drum near the slot so that the ends of the paper may be passed through their slots. With the paper in this position, the shafts are turned to draw the paper taut. This construction is far from satisfactory as the sheet is not uniformly tensioned, and replacement is a difficult operation as the parts are inaccessible.

The object of the present invention is to provide a drum of the type described, which is provided with means by which the working sheet may be held securely in position flat on the drum and under even tension, the improved holding means being of simple construction and permitting ready replacement of the sheet. In the new drum the ends of the working sheet are held securely, and when the drum is at rest the securing means may be rendered readily accessible, but when the drum is in operation it presents a substantially continuous cylindrical surface over

which the sheet lies smoothly and under uniform tension.

In the new drum the drum structure preferably includes a main drum member consisting of a cylindrical surface and end plates. A portion of the cylindrical surface is cut away and replaced by a plate preferably of segmental form which is movably mounted in the drum structure and provided with a gripping device at one end. This plate is movable to different positions, in one of which it closes the opening in the cylindrical surface, while in another position it lies at some distance from this opening. The drum member is provided with a gripping device adjacent to or at one side of the opening and in these gripping devices may be held the ends of the working sheet which extends around the drum and over the plate. When the plate is in open position, the distance between the gripping devices around the drum is less than this distance when the plate is disposed so as to close the opening. In order to secure the work sheet in position, the plate is moved away from the opening and the ends of the work sheet are inserted in the gripping devices and secured to it. The plate is now moved to close the opening and complete the drum, and in such movement the plate has a lever action which exerts tension on the sheet. Preferably the plate is pivotally mounted at a point within the periphery of the drum, and in open position the end of the plate carrying the gripping device projects outwardly beyond the drum surface, so that both gripping devices are exposed. The plate may then be swung to close the opening in any suitable way and at the same time put tension on the sheet, but preferably the plate is suitably balanced on its pivot so that when the drum is rotated, centrifugal force acts on the plate, moving it to closing position and holding it in that position throughout the rotation of the drum. By such movement of the plate, the sheet is tensioned and this tension is maintained by the centrifugal force. Also, it is preferable to provide the segmental plate with a light spring so that when the drum stops, the segment is caused to swing on its pivot away

55

from the opening, so that both gripping devices are exposed. During the period of rest, the work sheet is slack and as both gripping devices are exposed, replacement of the sheet is a simple matter.

The new drum includes various other features of improvement, as, for example, the gripping jaws are provided with operating means so that although they are ordinarily held in gripping position with considerable force, they may be opened for withdrawal or replacement of the abrasive material without difficulty. The drum is also provided with a layer of cushioning material on its outer surface and adjacent the opening in the drum surface through which the ends of the abrasive material pass, novel supporting means for the cushioning material are provided which prevent the tension placed on the abrasive material from flattening the cushioning layer to an extent such as to make the drum surface irregular. The new drum also includes convenient means for counterbalancing the weight of the segment and its associated parts and an exact counterbalancing may be accomplished without dismantling the drum.

For a better understanding of the invention, reference will be made to the accompanying drawing, in which

Fig. 1 is a view of the drum in side elevation, certain of the parts within the drum being indicated by dotted lines,

Fig. 2 is a sectional view on the line 2—2 of Fig. 1,

Fig. 3 is an end view taken as indicated by the arrow in Fig. 1,

Fig. 4 is an enlarged sectional view showing means for preventing the flattening of the cushioning layer by the taut abrasive material, and

Fig. 5 is a similar view showing a modified form of construction.

The new drum assembly includes the drum proper, a layer of cushioning material, and a work sheet. This work sheet may be of any suitable material, such as sand or garnet paper or cloth, leather, etc. For convenience, the work sheet will be referred to as paper, though it is to be understood that any suitable sheet material may be used for the purpose.

The drum comprises a substantially cylindrical member 10 provided with end plates 11 and preferably the cylindrical member and end plates are made in one piece by a suitable casting operation. The cylindrical member 11 is cut away to form an opening extending from one end plate to the other, and this opening under proper conditions may be closed by a segment member 12 which consists of a casting having a curved surface 13 and end plates 14 by which the member 12 is pivotally mounted on a shaft 15, the ends of which are received in bosses 16 in the drum

end plates 11. Attached to the segment member and to the inner wall of the casing is a spring 17 of light construction and so arranged that when the drum is at rest, the spring rocks the segment on its pivot to the position illustrated in Fig. 3, in which the end 18 of the segment projects outwardly beyond the cylindrical surface of the drum, while the end 19 lies within the drum surface. When the drum is in rotation, the segment member occupies the position shown in Fig. 2, due to the fact that the member is off-balance on its pivot and centrifugal force acting on the member will cause it to swing to the position illustrated. At its rear end, the segment member is provided with a shoulder 20 which abuts the inner face of the peripheral surface of the drum adjacent the opening in which the segment is disposed, when the segment is in its outward position (Fig. 2) and in that position the curved surface of the segment forms substantially a continuation of the outer surface of the drum, the end 18 of the segment lying close to the edge 21 of the cylindrical surface of the drum at the opening.

At its end 18, the segment member is provided with an inclined plate 22 formed as a continuation of the curved surface 13 and in the end members 14 of the segment member is mounted a shaft 23 on which is pivotally mounted the clamping jaw 24. One end 25 of this jaw is adapted to bear against the inclined plate 22 for gripping purposes, and the other end of the jaw is provided with a tail 26 which lies against a stud shaft 27 mounted in one end member of the segment member. A spring 28 encircling the shaft 23 is arranged to cause the jaw member to swing on its pivot to force the tail toward the shaft 27 and this shaft has a flat portion such that when the flat portion is presented to the tail, the spring 28 may swing the jaw member so that its gripping end 25 is forced tightly against the plate 22. The shaft 27 is provided with a boss 29 at one end, in which is a slot-like recess 30, and the end plate 11 adjacent the boss 29 is provided with an opening 31. By swinging the segment member on its pivot, the boss will be exposed through the opening 31 and a tool may be inserted in the recess 30 and the shaft rotated so that its curved portion bears against the tail 26 of the jaw and swings the jaw to move its end 25 away from the inclined plate 22. The jaw may thus be opened conveniently from the outside of the drum. When the tool is inserted through opening 31 into recess 30, the tool holds the plate 12 against the action of the spring 17.

Formed as a continuation of the outer drum wall adjacent the edge 21 is an inclined plate 32 and mounted on a shaft 33 extending from one end of the drum to the other is a clamping jaw 34 having a gripping portion 35 cooperating with plate 32, and a tail 36. The

shaft 33 carries a spring 28' normally forcing the jaw into gripping relation with respect to plate 32, in which position the tail 36 lies close to a stud shaft 37 mounted in a suitable boss in the end plate of the drum and carrying a bushing 38 at its exposed end, provided with a slot-like recess 39. The shaft 37 has a flat portion which is turned toward the tail 36 when the jaw is to perform its gripping action, but when the shaft 37 is turned by means of its bushing so that a curved portion of the shaft bears against the tail 36, then the jaw is swung to open position.

The outer surface of the drum is covered by a layer of cushioning material 40 which may be a sheet of sponge rubber or other suitable material for the purpose. This cushioning sheet is secured to the drum face at suitable points and extends over the segment, being secured to the end thereof which lies outside of the drum surface when the drum is at rest. The length of the cushioning layer is such that when the drum is in rotation, as illustrated in Fig. 2, the ends of the cushioning layer will lie close together and be separated only by the thicknesses of paper which pass between them and are gripped by the jaws.

In attaching the abrasive paper to the drum, the shaft 33 is turned so as to open the jaw 35 and one end of the abrasive paper is slipped between the jaw and the plate 32. When this end is in proper position, the shaft 33 is turned so as to release the jaw and the latter grips the end of the paper under the influence of its spring 28'. The free end of the paper is then wound around the drum and over the segment and the latter is swung manually on its pivot to bring the boss 29 opposite the opening 30. A tool is now inserted through the opening and the stud shaft 27 is rotated to the extent necessary to swing the clamping jaw to open position. The end of the paper is then placed between the jaw and its bearing plate and the stud shaft rotated to present its flat surface to the tail of the jaw, whereupon the jaw will grip the end of the paper tightly under the action of its spring. When the parts are released, the spring 17 will restore the segment to the position illustrated in Fig. 3. Both ends of the paper are now gripped in the clamping jaws, but the paper is not drawn taut against the cushioning surface. When the drum is rotated, however, centrifugal action swings the segment on its pivot to the position illustrated in Fig. 2, in which position the curved portion of the segment member forms a continuation of the main cylindrical part of the drum, and tension is placed on the paper which draws it taut and holds it in that position throughout rotation. As the paper is drawn taut, it has a tendency to flatten the edges of the cushioning member at the points 41 and 42 which are adjacent the point where

the ends of the paper pass into the drum to the jaws. To prevent such flattening action, I provide the end of the segment and the end of the drum at the point where the ends of the paper pass to the jaws with plates 43 and 44 which are secured to the respective parts in any convenient manner, as by small screws 45. These plates 43 and 44 are of thin sheet metal and project outwardly beyond the drum and segment wall for a distance somewhat less than the thickness of the cushioning layer. When the layer is compressed by the tension of the paper, the plates hold the layer in position and prevent compression to an extent which would cause the drum to have a flat surface at the opening through which the ends of the paper pass.

Instead of using plates 43 and 44, I may employ the arrangement illustrated in Fig. 5. Here the ends of the cushioning sheet are perforated and L-shaped plates 46 of thin sheet metal are placed over the ends of the sheet. These plates have countersunk portions 47 receiving the heads of screws 48 which pass through the cushioning sheet and into the curved surface of the drum and segment. The heads of the screws normally lie a considerable distance below the surface of the cushioning member before compression of the latter and the ends of the plates 46 pass around the ends of the cushioning member and overlie the ends of the segment and cylindrical surface of the drum, as indicated at 49. When the ends of the paper are drawn taut and the cushioning layer is collapsed, the sheet metal members 46 are forced downwardly toward the drum surface to a slight extent, but the portions of the plates which overlie the ends of the cushioning member prevent its being flattened by the tension of the paper to an extent sufficient to form a flat place on the drum.

It will be noted, Fig. 2, that the axis of the shaft 28 lies substantially in the plane of the gripping face of the inclined plate 22 and the bearings for this shaft similarly lie in the plane of the face of the plate. Likewise the shaft 33 with its bearings lies substantially in the plane of the operating face of the inclined plate 32. With this arrangement, the bearings serve as stops for the ends of the sheet of sandpaper or the like which is used to cover the drum.

In drums of this type used for surfacing floors, for example, it is very important that the paper should be under substantial tension which should not vary beyond certain limits. Accordingly, the paper used with a drum of any given size is cut to an exact length appropriate for that drum and when the paper is mounted on the drum the ends should be inserted in the jaws in such manner that there is a definite length of paper in the space from one jaw to the other around the drum. If the workman is careless and inserts the paper

70

75

80

in the jaws in such manner that the distance along the paper between the jaws is greater than it should be, the segment, when swung an operation of the drum, will not draw the paper right and as soon as the rotating drum 5 comes in contact with the surface to be operated on, the paper is likely to bunch up and produce an irregularity in the drum surface which not only results in the paper being injured but also injures the surface being 10 treated. If the paper is placed in the jaws with too short a length of paper extending around the drum and lying between the jaws, the tension placed on the paper by the segment as soon as the latter is swung by the 15 action of the centrifugal force is likely to be sufficiently great to rupture the paper and thus require the insertion of a new piece.

With the present construction, these difficulties are readily avoided. In inserting the 20 paper in position, the segment is swung outward in the direction suggested in Fig. 3 until both jaws are exposed. The workman inserts one end of the paper between the jaw and the 25 plate on the segment and in doing so, moves the paper until its end abuts the shaft bearings which thus serve as a stop. The paper is then wrapped around the drum and its other end bent around the edge of the opening 30 in the drum surface and its end inserted between the jaw 35 and plate 32. Here again, the end of the paper is moved along the inclined plate until it strikes the bearings for shaft 33 which serve as the second stop. 35 Since the paper is cut to an exact length appropriate for the drum and these stops are provided, it will be apparent that the workman can mount the paper in proper position without difficulty and in such manner that 40 there is an exact length of the paper lying between the jaws in the direction around the drum and this length of paper is just sufficient so that it will be properly tensioned and wrapped tight about the drum surface when 45 the drum is rotating. It will be noted that the edge of the drum opening and the edge of the segment around which the paper is wrapped are both relatively wide and the plates 22 and 32 are inclined at such an angle 50 that the paper is bent through an angle of less than 180° at its ends when being placed in position. The paper used in these drums is relatively stiff and it can not easily be bent through a sharp angle. With the present 55 construction, the paper is bent through an easy curve and by the provision of the stops, the workman has no difficulty in mounting the paper in position. It will be apparent that the placing of the shafts with their 60 bearings in the position illustrated provides a simple stop which serves the desired purpose of assisting the workman in mounting the paper in position, although stops of other construction might similarly be used.

65 When the plate is swung on its axis to a

position in which its projecting outer end is in outermost position, the inclined gripping surface of plate 22 lies at one side of a radius through the center of the cylinder and the outer edge of surface 22. The surface lies at 70 the same side of this radius as the other plate 32 mounted in the body of the drum. When the gripping surface on the plate 12 fulfills this condition, it is a simple matter to bend the end of the stiff abrasive sheet around the end of the cushion layer and around the edge of the plate 12 into position to be gripped by jaw 25. Should the inclined surface 22 lie at the other side of the radius referred to, the 75 extreme end of the sheet would have to be bent through a greater arc and because of the character of the sheet, its end could be inserted in the gripping jaw on the plate 12 only with the utmost difficulty.

The drum is mounted for rotation in any convenient manner on the shaft, as for example, the end plates may be provided with bosses 50 through which the shafts extend, the drum being secured to the shaft in any desired way. Since the segment, the jaws and their associated parts are at one side of the center of the drum, provision must be made to balance the drum and for this purpose a solid weight 51 is cast within the drum opposite the segment and extending from one end of the drum to the other. As this weight 51 will not ordinarily give an accurate counterbalance, the end plates of the drum are provided with open channels 52 in which suitable additional weights may be placed 95 from the outside of the drum. By a selection of the weights, the drum may be evenly balanced so that it will run without pounding.

It will be seen that in the new drum the paper may be placed in position on the surface of the drum and its ends secured in the gripping devices without the necessity of putting that tension on the paper which would be required to hold it rigidly in position during the operation of the machine. 105 With drums as heretofore constructed, the paper is wrapped about the drum and attached thereto and its ends are then drawn up so as to make the paper taut. This is a difficult operation and results in non-uniform tension which gives the paper a short life. 110 With the present construction the drum is so constructed that its periphery may be considerably reduced in length by swinging the plate so that the mounting of the paper in position and the securing of its ends is a simple operation, and it is not necessary that the paper should have its ultimate tension while its ends are thus being secured. It is 115 simply laid smoothly in position on the surface of the drum and its ends gripped. Thereafter the segmental plate may be restored to complete the cylindrical surface of the drum and in such movement of the segmental plate the tension is applied. After 120 130

the paper is put in position the plate may be restored to normal operating position in any convenient manner. For example, the plate may be swung manually and held in operating position by any convenient locking means. 5 I prefer, however, to construct the plate in the manner heretofore disclosed, so that centrifugal action will apply the force necessary to restore the plate to close the opening in the drum. I have found that in a drum thus 10 constructed, a segment of relatively light weight may be so balanced that at normal operating speed a tension of over one-hundred pounds may be placed on the paper. This tension is exerted gradually as the drum approaches operating speed, and during the gradual application of the pressure the paper is under uniform tension so that the stress is evenly distributed.

With the present drum it will be observed 20 that all of the operating parts are normally concealed but are readily accessible when occasion arises. It is not necessary, therefore, to remove the end plates of the drum, or otherwise take it apart if it should be desired 25 to get at the interior of the drum. The operating parts of the new drum are all of simple construction and may readily be manipulated so that replacement of the paper is a simple operation which does not require 30 any considerable amount of time. While the drum has been illustrated as consisting of a main body portion and end plates of integral construction, it will be apparent that the end 35 plates may be made separate from the body, and numerous other changes may be made without departing from the invention as set forth in the following claims.

I claim:

40 1. In a drum, a body having end walls and a cylindrical wall provided with an opening extending lengthwise of the drum axis and substantially from end to end of the drum, a plate of segmental form mounted within the drum on an axis lying between radial planes 45 passing through the edges of said opening, and balanced to be swung by centrifugal force to close the opening, a gripping jaw carried by the body and cooperating with a portion 50 thereof adjacent one side of the opening, a gripping jaw carried by the plate and cooperating with a portion thereof, the gripping jaw carried by the plate lying adjacent the first gripping jaw when the plate is in closing 55 position, a pair of stops, one associated with each gripping jaw and a surface sheet extending around the drum and over the plate, this sheet having one end held by the jaw on the plate and the other end held by the jaw on the drum, one end of the sheet passing around 60 the edge of the body at the side of the opening, and the other end of the sheet passing around one end of the plate.

65 2. In a drum, a body having end walls and a cylindrical wall provided with an opening,

a segmental plate pivotally mounted within the drum out of contact with said end walls, means within the drum operable when the drum is at rest for holding the plate with one end projecting beyond the surface of the drum, said plate being balanced to be swung by centrifugal force upon rotation of said drum to close said opening, a gripping device carried at the said end of the plate, a gripping device disposed within the drum at one side of the opening and adjacent the projecting end of the plate, a surface sheet extending around the drum and over the plate and having its ends held by the said gripping devices, and means operable from the outside of the drum for controlling the operation of the gripping devices.

3. In a drum, a body having a cylindrical wall, a portion of which is cut away to form an opening, a plate having a segmental surface pivotally mounted within the drum adjacent the opening, this plate being balanced to be swung by centrifugal force during rotation of the drum to a position in which it closes the said opening, a spring-pressed gripping jaw carried by the plate and cooperating with a portion thereof, a spring-pressed gripping jaw carried within the body and cooperating with a portion thereof, and means for moving the gripping jaws to open position.

4. In a drum, a cylindrical body a portion of which is cut away to form an opening extending lengthwise of the surface of the drum, plates closing the ends of the body, a plate having a segmental surface pivotally mounted in the end plates and adapted to be swung to close the opening in the body, means engaging the plate and operable for holding it in open position when the drum is at rest, the plate being so balanced as to be swung to closed position by centrifugal force in the rotation of the drum, and means carried by the drum and by the plate for gripping a surface sheet to be laid about the drum and over the plate.

5. In a drum the combination of a cylindrical body provided with end plate, the body having an opening in the wall thereof, a plate pivotally mounted within the body and adapted to be swung to close the opening, a gripping jaw carried by the plate and cooperating with a portion thereof adjacent one side of the opening, a gripping jaw carried by the drum and cooperating with a portion thereof at the said side of the opening, springs forcing the gripping jaws to operative position, and a shaft for each jaw adapted upon rotation to swing the jaw to open position, these shafts being operable from the outside of the drum.

6. In a drum, a body having a cylindrical wall, a portion of which is cut away to provide an opening, a plate mounted within the body and adapted to be moved to close the opening,

an extension from the plate at one end thereof turned toward the interior of the drum, a gripping jaw mounted in the plate and spring-pressed against the extension, this 5 plate having a tail, a shaft in the plate adjacent the tail, this shaft being operable upon rotation to bear against the tail and swing the jaw away from the extension, and gripping means carried by the body at one side of the 10 opening and adjacent the gripping means carried by the plate.

7. In a drum, a cylindrical wall having an 15 opening, a plate pivotally mounted within the drum and adapted to be swung to close the opening and complete the drum, means carried by the plate and by the drum adjacent one side of the opening for holding the ends 20 of a sheet, the plate being so mounted as to be moved to closed position by centrifugal force when the drum is rotating, and a spring within 25 the drum acting on the plate and operable when the drum is at rest to hold the plate in position free of the opening in the drum.

8. In a drum, a body having a cylindrical 30 wall with a longitudinal opening formed therein, the body being provided with a gripping surface lying inside the periphery of the body and extending inward from the outer surface of the body at one side of the opening 35 and at an acute angle to a radial plane passing through the edge of the opening and the axis of the drum, a gripping jaw arranged to cooperate with said surface and accessible through the opening, a plate mounted within 40 the drum and movable to close the opening, this plate having a gripping surface formed as an inward extension from the surface of 45 the plate, said gripping surface lying adjacent the first gripping surface when the plate is in closing position, and the surface on the plate lying at an acute angle to a radial plane passing through the axis of the drum and the edge of the plate from which said surface extends when the plate is in closing position, 50 and a gripping jaw mounted on said plate and adapted to cooperate with the gripping surface thereon.

9. In a drum, a body having a cylindrical 55 wall provided with an opening, a plate mounted in the body on an axis lying between radial planes passing through the edges of said opening, said plate being balanced to be swung by centrifugal force during rotation of the drum to close the opening and complete 60 the cylindrical wall of the body without substantial gaps, a gripping surface on said plate at one edge thereof and inclined to the surface of the plate, a gripping jaw cooperating with said plate, a gripping surface on the body at one side of the opening therein, and a gripping jaw cooperating with said gripping surface on the body, the gripping surface on the body, when the plate is in its extreme open position, lying at the same side of 65

a radial plane through the axis of the body and the outer edge of said surface as the second gripping surface.

In testimony whereof I affix my signature.
